UNITED STATES PATENT OFFICE.

JAMES VICTOR TOBEY, OF TARA, ONTARIO, CANADA.

DISPENSING SHOWCASE.

1,412,983.

Specification of Letters Patent. Patented Apr. 18, 1922.

Application filed April 29, 1921. Serial No. 465,559.

To all whom it may concern:

Be it known that I, JAMES VICTOR TOBEY, a subject of the King of Great Britain, and resident of the village of Tara, county of 5 Bruce, Province of Ontario, in the Dominion of Canada, have invented certain new and useful Improvements in Dispensing Showcases, described in the following specification and illustrated in the accompanying 10 drawings, that form part of the same.

The principal objects of the invention are to effectively display granular and free running goods in such a manner that the displayed goods will not remain stagnant but 15 will be utilized as the goods are dispensed.

A further object is to facilitate the dispensing of the goods and to provide means for submitting samples from the saleable stock in an attractive manner.

20 The principal features of the invention consist in the novel construction and arrangement of parts whereby a portion of the goods contained in the case is placed in a separate chamber having a transparent 25 front and the displayed goods and those contained in the body of the case are directed into a common dispensing chamber at the bottom, and whereby a passage from the bottom of the display chamber is intercepted 30 by a sampling drawer.

In the drawings Fig. 1 is a perspective front view of my improved display case.

Fig. 2 is a vertical mid-sectional view.

Fig. 3 is a transverse sectional view 35 through the line 3—3 of Fig. 2.

In the construction herein shown the case 1 is of rectangular form having a hinged cover 2 at the top and an opening 3 at the bottom of the back. A sloping bottom 4 40 slopes downwardly and forwardly from the top of the opening 3 and terminating a short distance above the bottom 5 and a short distance back of the front 6 of the case.

A glass frame 7 is arranged in the front 45 side of the case, the bottom thereof being arranged about one quarter of the total height of the case above the bottom of said case.

A panel 8 is spaced a short distance back 50 of the glass frame, being here shown supported in grooved guides 9 arranged on the inner side walls and slidable therein so that it may be readily removed to allow the inner side of the glass being cleaned. A

backwardly sloping partition 10 is arranged 55 in sloping guides 11 at the top of the panel 8.

A display compartment is thus formed at the front of the case into which the goods are poured when the case is being filled. The bottom of this compartment is formed by a 60 sheet metal strip 12 which is formed with upwardly sloping ends 13 and intermediate 65ly arranged sloping surfaced portions 14. Between the sloping surfaced portions of the strip 12 are formed the orifices 15, 16 and 17. The outer orifices lead into the dispensing chamber 18 at the forward end 70 of the sloping bottom so that the goods contained in the display chamber flow freely into the dispensing chamber as the goods 75 are removed though the flow is somewhat slower than that of the larger body in the main portion of the case.

A pair of parallelly arranged strips 19 extends inwardly from the front of the case 75 below the strip 12 and these meet and are secured to the sloping bottom 4 and between these strips back of the panel 8 is arranged a rigid cover 20 preferably of sheet metal 80 which directs the goods on to the side portions of the bottom 4 at each side of the strips 19.

Beneath the cover 20 and between the strips 19 is slidably supported a drawer 21 85 into which samples of the goods may be directed through the central opening 16 in the bottom 12 of the display compartment. A sliding shutter 22 is arranged immediately below the bottom 12 to close the opening 16 and when this is drawn out as shown in 90 Figs. 1 and 2 the goods will flow into the drawer.

The drawer 21 is preferably formed with a hopper bottom having a central opening 23 which is closed by a slide 24 which upon 95 replacing of the drawer may be opened to allow the sample to drop into the dispensing chamber.

The dispensing opening 3 at the back is closed by a suitable door 25 which is here 100 shown as arranged to slide in vertical guides though it may be arranged otherwise if desired.

In the use of this device, the goods are poured in at the top, care being taken to 105 fill the front compartment above the glass panel after the bottom of the main compartment is filled. The case is arranged in

a suitable place where the goods will be displayed to advantage but they will not be exposed to air or dirt. The goods are withdrawn by the use of a scoop from beneath the sloping bottom 4 and as the goods are withdrawn that contained in the display compartment flows down with that contained in the main portion, flowing through to holes 15 and 17.

10. If a customer desires a sample the shutter 22 is pulled out allowing the goods to flow into the sample drawer. The shutter is then closed and the drawer is drawn out. When the drawer is returned the slide 24 is 15 operated to clear the goods therefrom.

It will be understood from this description that a case such as described will enable the goods being handled in a most sanitary manner and they will be well displayed and 20 the displayed goods will always be in circulation.

What I claim as my invention is:—

1. In a dispensing showcase, a vertically arranged panel dividing the interior of the 25 showcase transversely and forming a shallow display compartment at the front, a glass panel in front of said display compartment, a bottom to said display compartment having openings therethrough and 30 sloping surfaces leading to said openings, a sloping bottom to the rear compartment sloping forwardly and downwardly, and a dispensing compartment below said sloping bottom and the bottom of said display 35 compartment.

2. In a dispensing showcase, a vertically arranged panel dividing the interior of the showcase transversely and forming a shallow display compartment at the front, a glass 40 panel in front of said display compartment, a bottom to said display compartment having an opening in the centre and openings

at either side of the centre and sloping surfaces leading to said openings, a dispensing compartment below the bottom of said display compartment and connected with said openings, a drawer arranged below the central opening, a rigid cover extending over said drawer and formed with sloping surfaces, a bottom presenting sloping surfaces 50 at each side of said rigid cover and extending forwardly below the bottom of said display compartment, means for closing the opening to said drawer, and means for emptying said drawer.

3. In a dispensing showcase, a vertically arranged panel dividing the interior of the showcase transversely and forming a shallow display compartment at the front, a glass panel in front of said display compartment, a bottom to said display compartment, having an opening in the centre and openings at either side of the centre and sloping surfaces leading to said openings, a dispensing compartment below the bottom 65 of said display compartment and connected with said openings, a drawer arranged below the central opening, and having a hopper bottom, a shutter closing the opening leading to said drawer, a slide closing the hopper bottom of said drawer, and a rigid cover extending over said drawer.

4. A dispensing showcase having a transparent front panel, a slideable panel vertically arranged behind said front panel, a hopper bottom between said panel and the front of the case, a hopper bottom in the rear portion of the case sloping forwardly and extending below the aforesaid hopper bottom, a dispensing chamber arranged below said hopper bottoms, and a door closing the dispensing chamber at the rear of the case.

JAMES VICTOR TOBEY,
